UNITED STATES PATENT OFFICE

165,254

COMBINED DISPLAY AND DISPENSING
STAND

John R. Warp, Chicago, Ill., assignor to Flex-O-Glass, Inc., Chicago, Ill., a corporation of Illinois

Application September 25, 1948, Serial No. 148,774

Term of patent 14 years

(Cl. D80—9)

To all whom it may concern:

Be it known that I, John R. Warp, a citizen of the United States, residing at Chicago, in the county of Cook and State of Illinois, have invented a new, original, and ornamental Design for a Combined Display and Dispensing Stand, of which the following is a specification, reference being had to the accompanying drawing forming a part hereof.

In the drawing:

Fig. 1 is a perspective view of a combined display and dispensing stand embodying my new design.

Figure 2 is an end elevational view with the measuring device shown in broken lines in Figure 1 omitted for convenience of illustration.

Fig. 3 is a top plan view thereof, with the measuring device shown in broken lines in Figure 1 omitted for convenience of illustration.

The dominant features of my design reside in the portions shown in full lines.

I claim:

The ornamental design for a combined display and dispensing stand, as shown and described.

JOHN R. WARP.

Certificate of Correction

Design No. 165,254

November 20, 1951

JOHN R. WARP

It is hereby certified that error appears in the above numbered patent requiring correction as follows:

In the drawing Figure 1 should appear as shown below instead of as in the patent—

and that the said Letters Patent should be read as corrected above, so that the same may conform to the record of the case in the Patent Office.

Signed and sealed this 26th day of February, A. D. 1952.

[SEAL]

THOMAS F. MURPHY,
Assistant Commissioner of Patents.
